UNITED STATES PATENT OFFICE.

WILLIAM FRED. SPENCE, OF ROCHESTER, NEW YORK.

SAFETY-PIN.

1,100,502.

Specification of Letters Patent. Patented June 16, 1914.

Application filed July 10, 1913. Serial No. 778,281.

To all whom it may concern:

Be it known that I, WILLIAM F. SPENCE, a citizen of the United States, and a resident of Rochester, in the county of Monroe and State of New York, have invented 5 a new and Improved Safety-Pin, of which the following is a full, clear, and exact description.

My present invention relates to safety pins, and more particularly to that character of safety pin which is provided with a guard in connection with the usual coil at one end thereof in order to prevent the fabric through which the pin is passed from working back into the coil and becoming caught, the object of my invention being directed to the provision of such a guard as will be simple and inexpensive to manufacture, adapted to ready insertion and securance, 10 without interfering with the normal action of the pin spring, and without projecting edges or parts such as would tend to fray or tear adjacent portions of the fabric in connection with which the pin is used. The 15 means by which I accomplish these objects I have clearly shown and will now proceed to describe in respect to the accompanying drawing, in which—

Figure 1 is a side elevation of a safety pin provided with my improvements; Fig. 2 is a sectional view therethrough taken on the line 2—2 of Fig. 1; Fig. 3 is a similar view taken on the line 3—3 of Fig. 1; Fig. 4 is a plan view of the guard disk removed; 20 Fig. 5 is a transverse section on the line 5—5 of Fig. 1.

Referring now to these figures, A represents the usual form of safety pin, consisting of a frame α carrying at one end a pin point housing α' , and having its opposite end connected to the pin bar α^2 by means of a coil α^3 , the single convolution of which is inclined as most clearly shown in Fig. 2.

In accordance with my invention I provide 45 a guard disk B of substantially the same diameter as the convolution of the coil α^3 within which the disk B is disposed, as clearly shown in Figs. 1, 2 and 3, the straight edge b of this disk abutting the inner portion of the convolution, and the remaining edge portion of the disk being confined between the convolution of the coil

and the adjacent ends of the frame and pin bars α and α^2 . In this manner projecting portions are eliminated and no portion of 55 the guard is exposed to endanger fraying and tearing of the fabric through which the safety pin is fastened. In order to effectively secure and prevent removal of the disk B from the position stated, I prefer- 60 ably distort the same within the convolution of the coil α^3 , and in a lateral direction by a sharp bending, as indicated at b' and most clearly shown in Fig. 2, so that a portion thereof extends or is deflected laterally 65 from the plane of the coil α^3 , and being within the coil, accidental displacement of the disk is prevented. It may be also seen by reference to Fig. 2 that the edge b of the guard disk, though straight as viewed in 70 plan, is necessarily curved or ogee shaped, as shown in Fig. 5, in order that the remaining portion of the disk edge shall follow and be gripped between the convolution of the coil and the frame and pin bars, 75 as before mentioned, requiring that the straight edge extend diagonally across the forward or inner portion of the spring convolution at a point within the coil.

It may be readily seen that the disk I 80 propose is not only simple in its structure and adapted for ready disposition and securance in place, but that by its particular structure and location the guard which I propose will neither interfere with the ac- 85 tion of the spring nor with the goods or fabric in connection with which the safety pin is used.

Having thus described my invention, I claim as new and desire to secure by Letters 90 Patent:—

1. The combination with a safety pin comprising frame and pin bars having a connecting coil at one end, of a guard plate disposed within the coil and spanning the 95 open space across the same with its edge engaged between the convolution of the coil and the adjacent portion of the frame and pin bars, and having its body laterally distorted inside of the coil convolution, 100 whereby to prevent displacement thereof.

2. In a safety pin, the combination with the frame and pin bars and spring coil connecting the same at one end, of a guard

comprising a piece of metal associated with the pin bar and preventing the entrance of fabric between said bar and the spring coil, said guard being laterally distorted within the coil and secured in place frictionally and being independent of positive connection with the coil or frame bar.

In testimony whereof I have signed my name to this specification in the presence of two subscribing witnesses.

WILLIAM FRED. SPENCE.
